UNITED STATES PATENT OFFICE.

JOSEPH L. KLAJON, OF JACKSON, MICHIGAN.

CAR-REPLACER.

1,077,478.

Specification of Letters Patent.

Patented Nov. 4, 1913.

Application filed July 12, 1913. Serial No. 778,809.

To all whom it may concern:

Be it known that I, JOSEPH L. KLAJON, a citizen of the United States, residing at Jackson, in the county of Jackson and State 5 of Michigan, have invented a new and useful Car-Replacer; and I do hereby declare the following to be a full, clear, and exact description of the invention, such as will enable others skilled in the art to which it app- 10 pertains to make and use the same.

This invention relates to a new and useful car replacer or re-railer.

An object of the invention is to provide a frog having a removable renewable wheel 15 replacing or re-railing rib, dove-tailed or otherwise secured to the frog. Heretofore, these ribs become worn in course of time in such wise as to prevent them from performing the desired result, whereupon the entire 20 car replacing frog has to be set aside. In the present device only the rib has to be renewed, thereby lessening the expense.

In practical fields it may be found necessary to subject the details of construction to 25 alterations, to which the patentee is entitled, provided the alterations fall within the scope of what is claimed.

The invention comprises further features and combination of parts, as hereinafter set 30 forth, shown in the drawings and claimed.

In the drawings:—Figure 1 is a plan view of a portion of a railroad showing the improved car replacer as applied. Fig. 2 is a transverse sectional view on the line 2—2 of 35 Fig. 1. Fig. 3 is a detail perspective view of one of the frogs. Fig. 4 is a sectional view on the line 4—4 of Fig. 3. Fig. 5 is a detail view of the renewable rib. Fig. 6 is a detail view of the frog. Fig. 7 is a sec- 40 tional view on the line 7—7 of Fig. 3. Fig. 8 is a sectional view on the line 8—8 of Fig. 1. Fig. 9 is a sectional view on the line 9—9 of Fig. 6.

Referring more particularly to the drawings, 1 designates the rails while 2 denotes the ties, whereas 3 and 4 denote the replacing frogs. Each frog is hollowed out upon 45 its under face, as shown at 5, and upon its upper face adjoining one of its sides (which is arranged at an angle to the rail) an elongated rib 6 is constructed. Each frog is inclined upwardly from the ties and toward the upper surface of the tread of the rail, so as to elevate the car wheels toward and 50 upon the tread of the rail, the rib 6 acting to guide the wheel toward the rail. The rib 6

of the frog 3 is provided with a supplemental rib 8, which, in side elevation, has its upper portion arranged at an obtuse angle to the upper face of the rib 6. This supplemental rib at one end is provided with 60 an abrupt incline 9 inclining down toward the tread of the rail. As a car wheel rides the supplemental rib to its highest point, the same then contacts with the abrupt incline 65 and is thrown down toward and upon the rail, so that the flange of the wheel will assume its proper position relative to the rail, while the other car wheel is guided in the position by the flange of the frog 4. 70 This supplemental rib 8 is renewable, owing to the same being dove-tailed into the flange 6 of the frog 3, as shown at 12. By means of this dove-tailed connection 12 an old supplemental rib 8 may be removed and a new 75 one placed in position, thereby renewing the structure of the frog 3. Pivoted in a recess of the under face of each frog adjacent the side, which recess is denoted by the numeral 13, is a bar 14, which is provided with a 80 recess 15 and a shoulder 15^a, to receive the base of the rail, thereby holding the frog in position.

The frog 4 is provided with a bulge 16, between which and the rib 6 a gully 18 is 85 constructed to receive the flange of the car wheel. Adjacent the bulge 16, the bottom of the gully 18 begins to incline downwardly and ends below the surface of the tread of the rail, as shown clearly in Figs. 8 and 9, so that the flange of the car wheel 90 will come in contact with the side of the tread of the rail. As the flange of the wheel is moving in the gully 18, the tread of the wheel engages the bulge 16. The end 17, of 95 the rib 6 of the frog 4, is spaced apart from the side of the tread of the rail, as shown.

The invention having been set forth, what is claimed as new and useful is:—

1. In a car or engine replacer, an outer 100 replacing frog having an upper surface inclined upwardly toward the tread of a rail and provided with a rib adapted to be engaged by the flange of a car wheel to guide the same toward the rail, a removable supplemental rib secured to the said rib adjacent the tread of the rail, and a securing hook provided with a shoulder to lock the frog to the rail.

2. In a car or engine replacer, an outer 110 frog having a rib adapted to be engaged by the flange of a car wheel so as to guide the

ear wheel toward the rail, said rib terminating in a removable renewable supplemental rib having dove-tailed connections with the said guiding rib, and a securing hook provided with a shoulder to lock the frog to the rail.

In testimony whereof I have signed my

name to this specification in the presence of two subscribing witnesses.

JOSEPH L. KLAVON.
